UNITED STATES PATENT OFFICE.

ARTHUR E. SMITH, OF LOS ANGELES, CALIFORNIA.

SYRINGE.

Application filed February 15, 1927. Serial No. 168,295.

This invention relates to syringes which are adapted for use with ampules.

The general object of this invention is to provide a syringe in which an ampule may be loaded in a syringe and automatically correctly positioned when the movable member of the syringe is arranged in operative position.

Another object of this invention is to provide a syringe having a movable member adapted to receive the ampule and provided with means which is adapted to expel the contents of the ampule.

Still another object of this invention is to provide a syringe wherein novel means is provided for forming a fluid tight joint between a portion of the syringe and an ampule to prevent leakage when the syringe is operated to expel the contents of the ampule.

20 Other objects and advantages of this invention will be apparent from the following description taken in connection with the accompanying drawings wherein:

Fig. 1 is a central vertical section of a syringe embodying the features of my invention.

Fig. 2 is an extended view of my improved syringe.

Fig. 3 is a cross section taken on line 3—3 of Fig. 1.

30 Fig. 4 is a bottom plan view of the ampule holding and plunger section of the syringe.

Fig. 5 is a top plan view of the main body or barrel of the syringe and

35 Fig. 6 is a sectional detail view of an ampule which may be used in connection with my improved syringe.

Referring to the drawing by reference characters I have indicated my improved syringe generally at 10. The syringe comprises a barrel or body 11 having a cross bar 12 adjacent its top and having its lower end internally threaded as at 13. The end of the barrel is chamfered outwardly as at 14, and the main portion of the barrel is provided 40 with spaced elongated apertures 11', the function of which will be explained hereinafter.

A tip 15 is in threaded engagement with the lower end of the barrel 12 and terminates 50 in a reduced externally threaded portion 16. The tip 15 is provided with a conical recess 17 and has a hollow discharge tube 18 soldered or otherwise secured in the reduced end portion 16. The tip 15 is also provided 55 at its upper end with internal threads as shown at 19.

A cone 20 is disposed in the conical recess 17 and tightly engages the discharge tube 18. The cone 20 is preferably made of rubber and is provided with a conical recess 21. 60 Adjacent the top of the rubber cone 20 on the surface of the recess 21, a circular ridge or bead 22 is provided. The rubber cone 20 is adapted to be maintained in position in the tip 15 by a ring 23 which is externally threaded to engage the internal threads 19 of the tip. A hypodermic needle 25 having a hub portion 26 is secured to the tip 15 by screw threaded engagement with the reduced end 65 of the tip.

An ampule holding and centering member 27 is adapted to be slidably mounted in the body. The ampule holder 27 comprises a tubular body 28 having spaced elongated apertures 29 therein and having a handle member 30 which includes a hub portion 31 threaded with the end of the body 28.

The end surface of the tubular body 28 is chamfered outwardly as at 32. A plunger rod 33 is secured in the hub portion 31 80 of the handle 30. This plunger rod 33 is provided at its lower end with an enlarged head 34.

An ampule which may be used in connection with my improved syringe is shown in 85 Fig. 6, is indicated generally by the numeral 35. This ampule is preferably made of glass and comprises a tubular body 36 having a restricted end portion 37 which is closed at the bottom by a tip 38. The tip 38 is rendered 90 readily removable from the portion 37 by providing an etched, scored, or molded notch 39 completely around the restricted portion 37. The large end of the tubular body 36 is closed by a stopper 40 which is preferably 95 made of rubber and which is slidable in the body 36. The outer end edge of the body 36 is preferably beveled as at 41.

When an operator desires to use my device the ampule holder 27 is removed from 100 the body 11 of the syringe. The tip of the ampule is broken and the ampule is inserted in barrel or holder 11 until the end of the ampule engages the cone 20 and the bead 22 engages the ampule. The neck 37 is fitted 105 over the tube 18 as shown in Fig. 1.

The centering member 27 is then inserted in the barrel. This member fits snugly within the tubular body of the barrel and as the member 27 slides in the barrel the bevel 32 engages 110 the bevel 41 on the end of the ampule and centers the ampule.

As the movement of the member 27 continues the plunger head 34 forces the rubber stopper 40 toward the restricted portion 37 and thus forces the contents of the ampule 5 into the discharge tube 18 and into the hypodermic needle 25.

As pressure is applied to the stopper the neck 37 of the ampule will be forced into tight engagement with the surface of the conical 10 part 21 of the cone 20 to thereby create a fluid tight joint between the two. Also as the neck 37 of the ampule is forced downward against the side walls of the conical recess 21 of the cone 20 the pressure against the side 15 walls will tend to force the bead 22 to grip the sides of the neck 37 of the ampule and thus form another fluid tight joint. This will prevent leakage, if for any reason there is a defect in the rubber cone or the fractured end 20 of the ampule which might allow the ampule contents to leak past the first mentioned joint formed by the contact of the fractured end of the ampule with the side walls of the conical recess in the cone 20.

25 The elongated apertures 11' in the syringe body 11 and the apertures 29 in the ampule holder 27 form viewing apertures through which the operator may observe to what extent the contents of the ampule has been 30 moved.

From the foregoing description it will be apparent that I have provided a syringe embodying novel features and which may be readily loaded, easily operated and which is 35 highly efficient in use.

What I claim is:

1. A syringe of the character described comprising a barrel, means in said barrel for engaging the end part of an ampule and a 40 member slidable in said barrel, said member having means rigid thereon for centering an ampule and also having means rigid thereon movable within an ampule for engaging a stopper in the ampule.

45 2. A syringe adapted to receive an ampule and having means at its discharge end to make fluid tight engagement with the end portion of an ampule, a member movable in said syringe, said member including a part adapted to engage the ampule to center it and a second part immovable relative to the first part and adapted to fit within the ampule.

50 3. In a syringe adapted to expel the contents of an ampule, a barrel, an ampule holder adapted to slide within said barrel, said ampule holder including a handle having a hollow tubular body rigid thereon adapted to engage the outer surface of an ampule, and a plunger rigid on the handle and arranged 55 within the hollow of said body, said plunger being adapted to fit within an ampule.

4. In combination in a syringe, a barrel, an ampule and an operating member, said

barrel comprising an elongated hollow body, said ampule including a hollow body having 65 means movable therein to force the contents out of the ampule and said operating member including a handle portion having a hollow sleeve thereon, said sleeve being adapted to slide within the barrel to center the ampule 70 in the barrel, said operating member including a plunger fixed with respect to said sleeve and movable into said ampule to engage said movable means and move said means.

5. A syringe adapted to expel the contents of an ampule comprising a barrel, an ampule holder adapted to slide within said barrel, said holder comprising a hollow tubular body having one end beveled outward, a handle on said ampule holder, and a plunger 80 rod within the hollow of said body, and engaging an end of ampule holder, said hollow tubular body of said ampule holder being of a size to fit over the outside of an ampule while said plunger engages a stopper to expel the 85 contents of said ampule.

6. In combination in a syringe, a barrel, an ampule and an operating member, said barrel comprising an elongated hollow body having means at one end for engaging an end 90 of the ampule, said ampule including a hollow body having a stopper movable therein to force the contents out of the ampule, said operating member including a handle portion having an open ended hollow sleeve thereon 95 adapted to slide within the barrel, means on said sleeve adapted to center the ampule in the barrel, said operating member including a plunger rigid thereon and movable into said ampule to engage said stopper and 100 move it to force the contents from said ampule.

7. In combination in a syringe, a barrel, an ampule and an operating member, said barrel comprising an elongated hollow body 105 having means at one end for engaging an end of the ampule, said ampule including a hollow body having a stopper movable therein to force the contents out of the ampule and said operating member including a handle portion having an open ended hollow sleeve thereon, said sleeve having a chamfered lower end adapted to slide within the barrel, said sleeve having an internal diameter slightly greater than the 110 outside diameter of the ampule, said sleeve being adapted to center the ampule in the barrel, said operating member including a plunger fixed with respect to said sleeve and movable into said ampule to engage said stopper and move it to force the contents from 115 said ampule.

In testimony whereof, I hereunto affix my signature.

ARTHUR E. SMITH.
